DESIGN.

F. MANKEY.

SURFACE ORNAMENTATION OF WALLS, &c.

No. 16,290.

Patented Sept. 22, 1885.

UNITED STATES PATENT OFFICE.

FREDERICK MANKEY, OF WILLIAMSPORT, PENNSYLVANIA.

DESIGN FOR THE SURFACE ORNAMENTATION OF WALLS, &c.

SPECIFICATION forming part of Design No. 16,290, dated September 22, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for the Surface Ornamentation of Walls, &c., of which the following is a specification, reference being had to the accompanying photograph, forming part hereof.

My design is intended for the ornamentation of surface of walls, doors, &c.; and it consists in the quadrilateral pyramidal elevations A, formed upon the surface in rows longitudinally the same. The elevations of one row alternate with the elevations of the next adjacent row. Between said elevations extend broad channels or spaces B and C, made in opposite diagonal directions across the panel. The effect is thus produced of widely sepa-

rated diamond-shaped projections upon the flat surface of the panel. The sides of said diamonds are curved.

I claim—

The design for surface ornamentation of walls, &c., substantially as herein shown and described, consisting in quadrilateral pyramidal elevations A, having curved sides, and widely separated and disposed in rows longitudinally the panel, the elevations of one row alternating with those of the adjacent row, and intervening broad channels or spaces, B C, extending diagonally in opposite directions across the surface.

FREDERICK MANKEY.
